[57] ABSTRACT

This disclosure describes multipair telephone cable connection apparatus for cross-connecting between a large number of pairs from a feeder cable to pairs of distribution cables. The connector typically is used in above-ground exchange area locations, operating in a system in which it is the only necessary interconnection point for about 500 subscribers. The closure is characterized by a square cross section, three vertical working faces, and an open side. Two of the working faces, opposite each other, mount quick-connect blocks to which distribution pairs are permanently terminated. The third face uses similar connector blocks to terminate pairs from the feeder cable. All cables enter through the closure base and pass through its interior. Jumpers are affected only on the exterior faces, and are arranged easily without becoming unmanageable.

SERVING AREA CONNECTOR**FIELD OF THE INVENTION**

This invention relates to telephone multipair cable connecting points; and specifically, to a connector interface between high capacity feeder cable and distribution cables.

BACKGROUND OF THE INVENTION

It is well recognized today that utility lines of all sorts should be below ground wherever possible. Where community planning permits laying out of telephone cable in advance of, or concurrently with, home construction, it is readily possible to connect, say, 500 homes with one or two telephone pairs each, and lead these pairs completely underground to a single aboveground cross-connect point. Here, the pairs can be connected to feeder cable pairs leading to a telephone central office. In order for cross-connect apparatus to handle such high density pair count, several problems must be solved to which existing art offers insufficient solutions.

Additionally, there is a general need throughout the telephone exchange area cable plant for a centralized closure-type control point at which to cross-connect feeder and distribution cable, in contrast to numerous aboveground sites such as prevails today. Accordingly, the below inventive objects are the motivating force behind the present invention:

- 10 to minimize the number of aboveground cable closures for a given service area;
- 20 to achieve all cross-connections between feeder and distribution cable for a given serving area in one place;
- 30 in a high pair-density closure, to divorce the cross-connect field completely from the incoming and outgoing cable pairs;
- 40 to minimize or eliminate the interference within a cross-connect field among jumpers;
- 50 to quickly and correctly identify in a large connecting field any given pair;
- 60 to achieve all of the above items in a piece of apparatus inexpensively and reliably.

SUMMARY OF THE INVENTION

Pursuant to the invention, a multipair telephone cable connection apparatus for cross-connecting between a large number of pairs from a feeder cable to pairs of distribution cables is characterized by a square cross-section, three working faces, and an open side. Two of the working faces, the ones opposite each other, mount quick-connect blocks to which distribution pairs are permanently terminated. The third face uses like-connecting blocks to terminate pairs from the feeder cable. All cables enter through the closure base and pass upwardly through its interior. Jumpers are effected only on the exterior faces, and are arranged easily using the corner channels as passageways.

The connector is mounted on an upright rectangular frame which anchors upon a precast concrete slab. In the slab center is a hollow opening through which feeder and distribution cable are lead. A rubber grommet and sealing tape assures watertight integrity through this lead-in point. The entire assembly is protected with a cover housing that is bolted to a narrow skirt connected to the slab.

The invention and its further objects, features, and advantages may be readily discerned from a reading of the detailed description to follow of an illustrative embodiment.

BRIEF DESCRIPTION OF THE DRAWING

FIG. 1 is a bottom view of the mounting slab and a side view of the base frame to which it mounts;

FIG. 2 is a top view of the mounting slab;

FIG. 3 shows the mounting slab accommodating several cables through its interior;

FIG. 4 shows the mounting frame secured to the slab and the cables grounded to the frames;

FIG. 5 shows the mounting frame erected with connector blocks installed and skirt in place;

FIG. 6 shows a portion of a connector block field with means for leading in conductor pairs;

FIG. 7 shows the closure with cross-connections partly made;

FIG. 8 shows the closure fully connected, looking in through the open side;

FIG. 9 shows the housing cover in position; and

FIG. 10 shows a pair of indexing strips installed.

All figures are either top, frontal, or side perspective sketches; and are numerically arranged essentially to correspond with the assembly sequence of the closure.

DETAILED DESCRIPTION OF AN ILLUSTRATIVE EMBODIMENT

As seen in FIG. 1, a base frame 10 consisting of four side angle irons 11 through 14 and four corner stakes 15 through 18, provides a rigid assembly for anchoring a concrete slab 19. The components of base frame 10 may be fastened together by any convenient means, such as bolts 20.

Slab 19 is a precast concrete member comprising a central bottom chamber 21 having a floor 22 with an opening 23 therein and, as seen in FIG. 2, a recess 24 around the walls of opening 23. The slab 19 may advantageously be square in plan view, as is chamber 21, floor 22 and opening 23. Chamber 21 is dimensioned to fit over the assembled side members 11-14 of the base frame 10. The latter is bolted to the floor 22, as with bolts 25.

Telephone cables, such as feeder cable 26 and distribution cables 27 and 28 are led through the base frame 10 and the opening 23 in the concrete slab. Then, as seen in FIGS. 2 and 3, a grommet 29 adapted to fit onto the recess 24 and having a number of cable holes 30 through 33 is prepared. Each cable 26-28 is given a sealing tape collar such as collar 34; and the grommet 29 is seated on recess 24. Sealing compound 35, seen in FIG. 3, then is poured between the collar 34 and the grommet holes 30-32. For the unused cable hole 33, a duct plug 36 is used as a removable seal.

In "planting" the closure base structure, it is preferable first to excavate around the buried cable to avoid damage during frame placement. Then, the base frame 10 is assembled and the cables are threaded through the top of the frame. The assembled frame is driven into the ground until its top is flush with the final grade. Thereafter, the frame is leveled, and the soil is tamped and backfilled into place until it is about three inches below the top of base frame 10. At this point, concrete slab 19 is lowered onto the top of frame 10. After the grommet is sealed, cable sheath from the cables 26-28 is removed beginning about nine inches above the grommet, to expose the pair groups.

The housing frame 40 shown in FIGS. 5 and 8 comprises a lower frame 41, seen in FIG. 4. Frame 41 consists of four angle iron uprights 42-45, the interior angle of which faces outwardly. The legs 42-45 connect at their lower ends to the sides of floor brackets 46-49, as by bolts 50. The floor brackets 46-49 in turn are bolted to the concrete slab 19, as with bolts 25.

The legs 42-45 are buttressed by horizontal struts 51-54, which also serve as grounding bars. These support cable straps such as 55, to which the respective cables 26-28 are clamped as with clamps 56. By conventional means, not shown, the metallic sheath of each cable is rigidly connected to the clamps 56 thereby to provide electrical continuity between the sheath and the base frame 10 for grounding.

The upper frame 60 of housing frame 40 consists of a top 61 bolted to the legs 42-45 as seen in FIG. 5. J-shaped cover guides, all designated 66, for use with cover 90 in FIG. 9, are fastened to the legs 42-45 and 62-65, there being two cover guides 66 associated with each leg.

CONNECTOR BLOCKS IN MOUNTINGS

Indexing strips 70, shown in FIGS. 5 and 6, are supported in a horizontal rows across three of the four vertical faces of the closure. Construction of these strips advantageously is in accordance with the disclosure of B. C. Ellis, Jr. in patent application Ser. No. 69,511, filed Sept. 10, 1970, assigned to applicants' assignee and which is hereby incorporated by reference.

Referring also to FIG. 10, index strips 70 are fastened at each of their respective ends to mounting brackets 71. Each strip 70 includes, for example, 50 opposed teeth pairs such as 72. As seen in FIG. 8, a backplate 73 is attached between the interior ends of the mounting brackets 71.

As seen in FIG. 10 each backplate 73 includes a right-hand column of passageways 74 and a left-hand column of 15 passageways 75. Pursuant to one aspect of the invention, the spaces between the adjacent index strips 70 are reserved alternately for cable pairs, and cross-connect or jumper pairs. The cable pair spaces are the ones containing the through-holes 74-75.

The index strip assembly shown in FIG. 10 is fastened to the upright legs 62-65 by suitable fasteners to the mounting bracket legs 71a. The index strips are placed across three of the four other faces of the structure, and from the lid 61 down to the struts 51-53. The fourth side of the structure is opened, pursuant to one aspect of the invention, as shown in FIG. 5 and FIG. 8.

Feeder cable 26, as shown in FIG. 8, is unsheathed to exposed 25-pair binder groups 76. In the telephone cable art, these binder groups 76 are color coded; and it is advantageous to use these codes to place the binder groups in a desired sequence in respective ones of the slots 74, 75. In this fashion, a given binder group color code is always assigned to a specific one of the slots 74, 75. The binder groups 76 are threaded through the cable slots 74, 75 and then sequentially into the index strips 70 seen in FIG. 10. The feeder cable conductors are placed in the index strips with light finger pressure, and then seated with a tool such as described in the aforementioned Ellis case.

Advantageously, the feeder cable 26 is connected to the closure face opposite to the open side so that the two faces flanking it are available to receive, in the same fashion, pairs from the distribution cables 27, 28. Designation strips 77, shown in FIGS. 5 and 6, are placed over the distribution feeder cable pairs after the latter have been connected in the foregoing fashion.

In the case of the embodiment being described, it is contemplated that each pair from the feeder cable 26 shall be connected with two specific pairs of the distribution cable 27, 28. Cross-connecting is achieved by jumpers between connector blocks 80 which are placed over the indexing strips 70 in the manner shown in FIG. 10. The connector blocks 80 are substantially those described in the aforementioned Ellis patent application; and their manner of insertion onto the strips 70 likewise is described there.

In accordance with some cable pair assignment plan, the jumpers 85, shown in FIG. 7, are led from the appropriate connector blocks 80, associated with the feeder cable 26, on through the fanning slot 78 formed in the sides of bracket 71, down the jumper cable corner channel formed by the vertical bracket sides and the associated upright leg such as 62-65, and thence in through the distribution cable fanning slot 78, to be connected to a second appropriate connector block 80 associated with one of the distribution cables 27, 28. Jumper wire guides 86, disposed along the length of the jumper channels shown in FIG. 7 help to maintain good housekeeping for the jumpers.

After all terminations have been made and prior to placing 70 cover 90, weather caps 57 are placed around at the break in the sheath for each cable 26-28, and plugging compound is poured in to build a water dam to protect the cable cores.

A skirt assembly, that advantageously is in two pieces 92 and 93, as seen in FIG. 5, is fastened to the lower frame as 75

sembly 41. The skirt assembly 92, 93 includes an upper recessed lip 94. The cover 90 fits onto the lip 94 in the manner shown in FIG. 9; and is secured thereto by two bolts 96 (only one shown). The manner of covering the closure housing may, however, be varied to include mechanisms such as doors that are vertically hung so as to form the cover 90 when closed as in FIG. 9, but by being hinged vertically open as standard doors.

It is to be understood that the embodiments described herein are merely illustrative of the principles of the invention. Various modifications may be made thereto by persons skilled in the art without departing from the spirit and scope of the invention.

What is claimed is:

1. Apparatus for interconnecting conductor pairs from two or more multipair telephone cables comprising:

a multisided frame having an interior corridor;
means for leading incoming and outgoing multipair telephone cables upwardly into said corridor;
means for supporting the ends of pairs from each said incoming cable in respective flat vertical fields upon a respective one of said sides, said means comprising a plurality of index strips arranged on said fields in horizontal rows, and first and second brackets and a connecting backplate mounted to said frame for rigidly mounting said index strips;

the spaces between successive adjacent pairs of index strips alternately being reserved for pairs from said incoming or outgoing cables, and for jumper wires; and

jumper wire channels comprising vertical corridors between adjacent sides of said frame, said corridors being partially defined by adjacent sides of said index strip mounting brackets.

2. Apparatus for interconnecting the pairs of a multipair telephone feeder cable with pairs from one or more multipair telephone distribution cable comprising:

a four-sided upright frame having an open bottom, an interior or corridor, and four exterior sides;
a base frame comprising four ground stakes connected by a square top frame;
a concrete slab having a bottom chamber for mounting upon said base frame top, a central opening for receiving said distribution and feeder cables, and grommet means for sealing said central opening when said cables are in place;

means for metallically connecting said base frame and said four-sided frame through said slab;

indexing strip means for terminating said feeder cable pairs upon a selected exterior side of said equipment;

indexing strip means for terminating the pairs of said distribution cable on either or both of the two said exterior sides adjacent to said feeder cable exterior side; and
means including the vertical exterior zone between the respective said exterior sides for channeling cross-connecting jumper wires between selected pairs from said feeder cable side and selected pairs from said distribution cable sides.

3. Apparatus pursuant to claim 2, wherein said jumper wire channeling means includes jumper wire guide means comprising one or more pairs of opposed J-shaped loops mounted on each of the four corners of said upright frame.

4. Apparatus pursuant to claim 3, further comprising indexing strip mounting means comprising:

a backplate disposed across three of said four exterior sides; first and second brackets extending outwardly at right angles from each said backplate, said indexing strips being attached in horizontal rows between said brackets, said brackets further comprising fanning strips for accommodating said jumper wires, and said backplate including slots at both ends of each alternate backplate region defined between adjacent said index strips, said slots accommodating pair groups from said cables.

5. Apparatus in accordance with claim 4, wherein said four-sided frame further comprises four angle-iron legs disposed in a square configuration with their interior angle facing outwardly, horizontal bars connecting adjacent ones of said legs slightly above their base, said bars including rigid straps for supporting said distribution and feeder cables and for grounding metallic sheath of said cables.

6. Apparatus pursuant to claim 5, further comprising a two-

piece skirt assembly mounted from said concrete slab around and to the base of said equipment, said skirt assembly including a recessed horizontal lip, and a housing cover cross-sectionally the same as the skirt assembly, supported on said lip.

5 7. Apparatus according to claim 6 wherein said grommet further comprises cable holes, each cable having a plastic collar in the vicinity of said grommet.
